INERTIA OPERATED PUMPING MECHANISM

Original Filed April 10, 1922

FIG. I.

INVENTOR.

Fred B. MacLaren

BY

Chester G. Brundell, ATTORNEY.

UNITED STATES PATENT OFFICE

FRED B. MACLAREN, OF JAMAICA, NEW YORK, ASSIGNOR TO CHESTER H. BRASELTON,
OF NEW YORK, N. Y.

INERTIA-OPERATED PUMPING MECHANISM

Application filed April 10, 1922, Serial No. 551,069. Renewed October 31, 1927.

This invention relates to improvements in fuel feed apparatus of the type adapted to be operated by vibrations imparted thereto, and has for its principal object the provision of vibration operated pumping means for supplying liquid fuel from a supply tank at a lower level than the engine carburetor to an auxiliary tank above the carburetor level.

10 Another object of my invention is the arrangement of the auxiliary tank and pumping mechanism therein so that an automatic control is effected whereby the maximum quantity of liquid within such tank at any 15 time may be controlled.

Another object is to divide the auxiliary tank into a lower or fuel chamber and an upper or damping chamber. The two chambers being connected by a relatively small 20 aperture, and the damping chamber serves to provide an automatic regulating means for controlling the height of the liquid in the fuel chamber.

Other objects and advantages will be apparent from the following description in which reference is had to the accompanying drawing forming a part of this specification, and in which similar reference numerals designate similar parts throughout the several 30 views.

In the drawings Figure I is a diagrammatic side elevation of an automobile equipped with my improved apparatus.

Figure II is a central longitudinal section 35 through the auxiliary tank and vibration operated pumping mechanism.

Referring now to the drawings, the numeral 5 designates the chassis of an automobile having the usual wheels 6, engine 7, rear fuel supply tank 8, carburetor 9, and my improved auxiliary tank 10 enclosing the pumping mechanism. The auxiliary tank 10 is herein shown as secured upon the front of the dashboard 11, although this may be 40 mounted in any convenient position upon the automobile at a sufficient height to enable liquid in the auxiliary tank to flow to the carburetor by gravity. The tank 10 is preferably cylindrical and is provided centrally of its lower wall with an opening 12

having an upturned flange adapted to position a cylinder 13 extending upwardly within the tank for a relatively short distance. The lower extremity of the cylinder 13 is adapted to be closed by a valved bushing 55 14 with which a coupling 15 is connected leading to the feed pipe 16 connected at its rear extremity with the fuel supply tank 8. A coupling 17 leads from the floor of the tank 10 to the feed pipe 18 connecting the auxiliary tank to the carburetor 9.

The valve in the bushing 14 may be of any desired construction, and is herein shown as comprising a ball 19 arranged in a chamber 20 and adapted to normally seat upon 65 and close the aperture 21 leading to the supply pipe 16. An aperture 22 connects the chamber 20 with the interior of the cylinder 13. A plunger 23 surmounted by a weight 24 together forming an inertia member—is 70 adapted to snugly fit at its lower extremity within the cylinder 13, a brass or other soft metal cap 25 being suitably pressed upon the plunger 23 and machined to snugly fit 75 within said cylinder. An outlet valve for the passage of liquid within the cylinder to the interior of the tank 10 is provided by aperturing the cap 25 and normally closing such aperture by a ball 26, the valve chamber surrounding such ball connecting 80 with an upper opening 27 leading through the sides of the plunger into the tank 10. For convenience in construction the aperture 27 is preferably formed as a slot extending from side to side across the plunger and the valve 85 chamber is an enlargement of the lower extremity of said slot. It will be understood however, that this construction may be changed at will and that the illustration herein is only by way of exemplification. 90

The inertia mechanism is normally maintained with the plunger 23 raised by means of a coil spring 28 surrounding the plunger and extending between the lower surface of the weight 24 and the floor of the tank. The weight is guided in its movements relatively to the shell of the tank by means of a separation plate 29 having a central aperture 30 with downturned flange 30' of a diameter only slightly greater than the diameter of 100

the weight 24, whereby the weight is surrounded by the guide flange 30' and fits snugly therein. The separation plate 29 also forms the lower wall of a damping chamber 31 between such plate and a cap 32 enclosing the top of the tank 10. In the illustrated embodiment we have shown the separation plate 29 and cap 32 as secured over the outwardly extending flange 33 of the tank by the same screws 34. This construction permits a ready assembly and accurate machining for centering all of the devices with their guiding flanges in alignment. Thus by accurately turning the periphery of the flange 33 and then bending the outer portion of the separation plate 29 thereover after the circular flange portion 35 thereof has been accurately machined on its inner surface I am enabled to quickly and accurately center the separation plate within the tank 10. By then constructing the cap 32 with a downturned flange 36 accurately fitting over the circular flanged portion 35 of the separation plate the cap may also be quickly assembled with its central aperture 36' in alignment with the guide flange 30 of the separation plate. The central aperture 36' of the cap is flanged substantially as shown to guide the rod 37 projecting upwardly from the inertia member. A small buffer spring 38 may be provided between the cap 32 and the upper portion of the weight 24 to prevent chattering of the moving parts. The upper portion of the weight 24 is preferably enlarged, as at 39 and provided adjacent its lower edge with an accurately machined wall of only slightly less diameter than the interior of the cylindrical portion 29^a of the separation plate. This construction enables a suction to be created within the cylindrical portion 29^a whenever relative movements of the inertia member and tank are imparted and this suction is used for regulating the height of the liquid within the tank 10 as hereinafter described. A relatively small aperture 40 is arranged in the lower wall of the separation plate 29 and a similar aperture 41 in the upper portion of the cylindrical member 29^a, both of which connect the damping chamber 31 with the fuel containing chamber in the lower portion of the tank 10.

In operation the vibrations of the automobile as it rolls along the road is sufficient to set in motion the tank 10, which, it moves vertically relatively to the inertia member formed by the plunger 23 and the weight 24, which because of its great mass is comparatively slow to vibrate and can be considered as remaining in a substantially stationary position. The downward movement of the tank 10 tends to lower the cylinder 13 relatively to the plunger 23 creating a suction which lifts the ball 19 from its seat and draws in liquid from the supply tank 8 through the feed pipe 16. The upward movement of the

tank 10 and cylinder 13 upon the plunger 23 tends to close the ball valve 19 and force the liquid then within the cylinder 13 into the fuel chamber in the lower portion of the tank 10 by elevating the ball 26 and passing through the slot 27 in the plunger. The next downward movement of the tank relatively to the inertia member will again draw liquid fuel into the cylinder 13, and this alternate admission and ejection from the cylinder 13 will be continued until the liquid within the tank 10 has reached a predetermined level which is controlled in the following manner. As soon as the liquid within the tank 10 has reached the height of the small aperture 40 in the separation plate 29 the next downward movement of the tank relatively to the inertia member will create a suction which will draw liquid fuel from the fuel chamber of the tank 10 through the aperture 40 into the damping chamber 31. Up to this time the vibrations had forced air through the aperture 40 alternately in opposite directions and so the movement of the enlarged portion 39 of the weight 24 within the separation member 29 had had no effect upon the pumping mechanism. When, however, liquid reaches the level of the aperture 40 the liquid is drawn into the portion 29^a of the damping chamber on the downward movement of the tank 10, which liquid cannot be forced through the aperture 40 again on the next upward movement of the tank 10 because of the small diameter of the aperture. The next downward motion of the tank then draws more liquid into the damping chamber which cannot all be expelled on the next upward movement of the tank. In this manner the liquid within the damping chamber gradually increases in quantity until it serves to prevent any relative movement between the tank and the inertia member, offering such a resistance to relative movement downward that the inertia member will be moved in each direction simultaneously with the shell of the tank.

The feeding of liquid from the fuel chamber of the tank 10 to the carburetor 9 will continue unabated until the level of the liquid within the fuel chamber drops below the aperture 40, whereupon the liquid within the damping chamber will be expelled into the fuel chamber and the pumping mechanism will again be set in motion to enable further suction of liquid fuel from the supply tank 8.

The invention is a modification of those shown in the applications filed jointly with Chester H. Braselton entitled "Inertia pump" and "Vibration operated pumping mechanism," Serial Nos. 532,718 and 533,493 respectively, and filed Jan. 30, 1922 and Feb. 1, 1922, respectively.

Having described my invention what I claim is:

1. In a fuel feeding mechanism, a supply

5 tank, an auxiliary tank connected therewith, an outlet pipe connected to the auxiliary tank, means for pumping liquid from the supply tank to the auxiliary tank comprising a cylinder secured to the floor of the auxiliary tank, a weighted plunger fitting into the cylinder and forming an inertia member, a spring for normally maintaining the plunger in raised position, a separation plate surrounding the 10 plunger and adapted to divide the tank into upper and lower compartments, said separation plate having an aperture therein connecting said compartments, and an enlarged portion on said plunger adapted to cooperate 15 with said upper compartment to form a dampening chamber.

2. In a fuel feeding mechanism, a supply tank, an auxiliary tank connected therewith, an outlet pipe connected to the auxiliary tank, 20 means for pumping liquid from the supply tank to the auxiliary tank comprising a cylinder secured to the floor of the auxiliary tank, a weighted plunger fitting into the cylinder and forming an inertia member, a spring for 25 normally maintaining the plunger in raised position, a separation plate surrounding the plunger and adapted to divide the tank into upper and lower compartments, said separation plate having an aperture therein connecting said compartments, and guide means 30 for the relative movements of the tank and the inertia member, cooperating with said upper compartment to form a dampening chamber.

35 3. In a fuel feeding mechanism, a supply tank, an auxiliary tank connected therewith, an outlet pipe connected to the auxiliary tank, means for pumping liquid from the supply tank to the auxiliary tank comprising a cylinder secured to the floor of the auxiliary tank, a weighted plunger fitting into the cylinder and forming an inertia member, a spring for 40 normally maintaining the plunger in raised position, a separation plate surrounding the plunger and adapted to divide the tank into upper and lower compartments, said separation plate having a cylinder portion larger than said weighted plunger and adapted to receive an enlargement formed of a portion 45 of the inertia member and also having an aperture therein connecting the lower compartment of the tank with such cylinder portion.

4. In a fuel feeding mechanism, a tank 55 having upper and lower compartments, a separation plate having a plurality of apertures between said compartments formed with an enlarged central cylindrical portion, vibration operated means within the tank for drawing liquid fuel into the lower compartment 60 including an inertia member passing through the separation plate and having an enlarged portion fitting into the cylinder portion of such plate, whereby the separation plate acts 65 as a guide for the inertia member.

5. In a fuel feeding mechanism, a tank having a cylinder mounted on its lower wall, a plunger fitting in the cylinder, a weight carried by the plunger, a separation plate dividing the tank into upper and lower compartments and having a central aperture therein for the reception of said weight, said plate being formed with an enlarged cylindrical portion having an aperture therein connecting the upper and lower compartments of the tank, and means carried by the plunger for movement within the cylinder portion of the plate to regulate the quantity of liquid within the lower compartment. 70 75

6. In a fuel feeding apparatus, a tank, vibration operated pumping mechanism therein including an inertia member, a separation plate dividing the tank into a lower fuel compartment and an upper damping compartment, said plate having a plurality of apertures connecting the compartments and also having an enlarged cylinder portion adapted to snugly receive a portion of the inertia member to form an auxiliary piston whereby the height of the liquid in the fuel compartment is controlled. 80 85

7. In a fuel feeding mechanism, a tank having upper and lower compartments, a separation plate having a plurality of apertures between said compartments, vibration 90 operated means within the tank for drawing liquid fuel into the lower compartment, said means including an inertia member passing through the separation plate, and means attached to the inertia member above the separation plate and cooperating therewith to form a dampening chamber. 95 100

In testimony whereof, I affix my signature.
